UNITED STATES PATENT OFFICE.

JOHN DOMINY, OF GOODELL, IOWA.

TOY.

1,253,360.

Specification of Letters Patent. Patented Jan. 15, 1918.

Application filed May 9, 1916. Serial No. 96,403.

To all whom it may concern:

Be it known that I, JOHN DOMINY, a citizen of the United States, residing at Goodell, in the county of Hancock and State 5 of Iowa, have invented certain new and useful Improvements in Toys, of which the following is a specification.

This invention relates to an improvement in toys and more particularly to a mechanically 10 operated toy in which a figure is mounted to be actuated and be given grotesque movement or movement similar to the antics of the jig dancer.

An object of my invention is to provide 15 such a toy which may be very simply and inexpensively manufactured and which has the main working parts of the operating mechanism inclosed so that this mechanism cannot be readily tampered with by children.

20 A further object lies in so constructing the operating mechanism that it is of the clock-work type and may be set to be held against operation or to operate at the pleasure of the user, and further to provide means 25 by which a balance is maintained in the operating mechanism so that the weight of the figure which is to be operated will not act as a drag to prevent successful operation of the device.

30 With the above and other objects in view, my invention consists in such novel features of construction and combination of parts to be hereinafter set forth in connection with the drawings and then more particularly 35 pointed out in the claims.

In the drawings:

Figure 1 is a view in front elevation showing the entire device.

Fig. 2 is a view in end elevation of the disclosure in Fig. 1.

Fig. 3 is an enlarged view of the operating mechanism to further disclose the operative parts thereof.

Fig. 4 is a view in end elevation of the 45 operating mechanism containing case.

The main structure of the device comprises a base 1 which has a standard 2 mounted in an upright relation adjacent to one side of the base and a case 3 is mounted 50 on this upright standard 2 so that it has one end thereof disposed substantially centrally over the base 1.

The case 3 has a clock-work mechanism of the usual form mounted therein and a winding means 4 is provided to permit winding 55 of the spring of the clock-work mechanism

to bring the spring to a tension to give the desired operating impetus to the mechanism. The escapement shaft 5 is positioned adjacent to one end of the case 3 and the escapement dog or anchor 6 is mounted on the shaft and is provided with the usual pallets which engage with the teeth of the escapement-wheel 7 which is driven from the clock-work mechanism, these parts being 60 substantially identical with similar parts as in ordinary clock-work or spring motors. A control lever 8 is brought up through the case 3 and is extended to one side where it will be accessible to the user to permit turning of the same to stop the operation of the clock-work or to permit turning to allow 65 operation thereof.

An arm 9 is mounted on the shaft 5 and is extended through a slotted opening 10 70 formed in the end of the case, this arm being so arranged that as the parts operate and the dog or anchor 6 is rocked, the arm 9 is given oscillatory or vibratory movement. In the first instance I have shown the figure 80 to be operated as being that of a doll form as generally indicated at 11, and it is to be noted that the arms 12 and the legs 13 are made separate from the body portion and are hingedly mounted thereon. The lever 9 85 is provided on its outer end with a ring or hook 14, and a cord or other flexible element 16 is connected through a ring 15 formed on or carried by the figure 11 and is connected at its remaining end with the looped or 90 hooked portion 14 of the lever 9.

By making the cord or other flexible element 16 of such length that the feet of the figure 11 will come in contact with the upper surface of the base 1 and will be raised above 95 the same, a structure is accomplished in which very life-like movements are imparted to the hingedly connected or jointed arms and legs of the figure as the lever 9 is oscillated or vibrated through actuation by the 100 clock-work mechanism. As the weight of the figure 11 is supported on the arm 9 during a part of the operation, it is preferable that a counterweight 17 be mounted on an arm 18 which is extended to the opposite 105 side of the shaft 5, and in this way the weight of the figure is in a measure counterbalanced and the escapement mechanism is given better operation.

In the use of the toy, the control lever 8 110 will be moved to a position to stop movement of the parts of the clock-work mecha-

nism and then by turning the winding key the spring will be coiled in the usual manner, then when the operating lever is moved to a position to release the clock-work mechanism, the escapement means will cause the 5 arm or lever 9 to be given vibratory or oscillatory movement and through the connection of the cord 16 with the figure 11, this figure will be given up and down movement 10 with a somewhat sharp and jerking action which will cause the arms and legs to move with respect to the body and will give the desired jiggling appearance to the figure.

While I have herein shown and described 15 only one specific form of the device, it will be understood that two or more figures might be attached on the cord 16 that modifications might be resorted to in the arrangement of the parts as hereinbefore set forth, 20 and that still other changes might be made without departing from the spirit and scope of my invention, and hence I do not wish to be limited to the exact disclosure but only to such points as may be set forth in the claims.

25 I claim:

1. A mechanical toy comprising a base, an upright standard mounted on said base, an operating mechanism carried at the upper end of the standard, said operating

mechanism including an arm to which vibratory movement is imparted, a figure having the depending members thereof jointed, and a flexible member by which the figure is suspended from the arm. 30

2. A toy comprising a base, an upright standard mounted on said base adjacent one side thereof, a case mounted on the upper extremity of said standard in overhanging relation, an operating mechanism mounted within the case, said operating mechanism 35 having an arm extending from the case with the outer end thereof substantially centrally located over the base and said arm having vibratory movement imparted thereto by actuation of the operating mechanism, a figure having the depending members thereof 40 loosely connected, and a cord connected with the outer end of said arm by which the figure is suspended therefrom with the lower extremities resting substantially upon 45 the base. 50

In testimony whereof I affix my signature in presence of two witnesses.

JOHN DOMINY.
